UNITED STATES PATENT OFFICE.

RUBIN CAPLAN, OF PITTSBURG, PENNSYLVANIA.

WATCHMAKER'S TOOL.

No. 902,939.

Specification of Letters Patent.

Patented Nov. 3, 1908.

Application filed June 5, 1908. Serial No. 436,894.

To all whom it may concern:

Be it known that I, RUBIN CAPLAN, a subject of the Emperor of Russia, residing at Pittsburgh, in the county of Allegheny and State of Pennsylvania, have invented certain new and useful Improvements in Watchmakers' Tools, of which the following is a specification, reference being had therein to the accompanying drawing.

10 This invention relates to a watch maker's tool, and the primary object of my invention is to provide a tool for easily and quickly removing rollers from the spindles of balance wheels or similar horological wheels.

15 A further object of this invention is to provide a simple, inexpensive and durable tool that can be easily manipulated.

20 My invention comprehends a pair of pincers or pliers for gripping the roller of a balance wheel. Swiveled upon the pincers or pliers is a support for an adjustable screw, which is brought into engagement with the spindle of a balance wheel for forcing said spindle out of engagement with the roller held by the pincers or pliers.

25 The detail construction entering into my invention will be presently described and then specifically pointed out in the appended claim.

30 In the drawings, Figure 1 is a side elevation of an implement constructed in accordance with my invention, Fig. 2 is a top plan of the same, Fig. 3 is a bottom plan of a portion of the tool, Fig. 4 is an enlarged end view of the tool, partly broken away and partly in section, and Fig. 5 is an enlarged longitudinal sectional view of a portion of the tool.

35 In the accompanying drawings 1 and 2 designate the handles which are curved or bowed outwardly and have their forward ends enlarged as at 3 and 4, terminating in the gripping jaws 5 disposed at an angle to the handles 1 and 2. The confronting faces 40 of the gripping jaws 5 are longitudinally grooved, as at 6, and are provided with confronting transversely disposed grooves adapted to provide a central opening 7 when the jaws 5 are closed.

45 50 The confronting edges of the jaws are disposed at an angle, as at 8, when the jaws are closed, whereby when said jaws are opened and are placed in engagement with a roller 9 of a balance wheel 10, the confronting edges 55 of said jaws will be parallel and will firmly

hold the roller 9 while the spindle 11 of the balance wheel is forced from the roller.

The enlarged end 3 of the handle 1 is cut away upon its under side as at 12, to accommodate the enlarged end 4 of the handle 2, 60 said enlarged end also being cut away to receive the enlarged end 3 of the handle 1, whereby the upper and lower faces of the enlarged ends will lie flush with the upper and lower edges of the handles 1 and 2. 65

To connect the enlarged ends 3 and 4 I employ a rivet 13, which is revolvably mounted in the enlarged ends 3 and 4, as best shown in Fig. 5 of the drawings. Extending longitudinally of the rivet 13 is a revolvable screw 70 14, and fixed upon the threaded end 15 of said screw is a support 16 having an adjustable screw 17. The upper end of this screw is provided with a head 18, while the lower end is reduced and provided with a socket 75 19 adapted to receive the spindle 11 of the balance wheel 10, as will presently appear.

In operation, the roller 9 is gripped between the jaws 5, said roller being centered in the jaws by virtue of the grooves 6 and the opening 7. With the roller held in this manner and the balance wheel 10 beneath the jaws, the support 16 is swung until the screw 17 is directly above the spindle 11. The screw 17 is then adjusted to screw downwardly to engage the spindle 11, the socket 19 receiving the reduced end of the spindle. A further downward movement of the screw 17 forces the spindle 11 from the roller 9, the balance wheel 10 dropping upon a suitable 90 support, as a workman's bench, (not shown), while the roller 9 is retained between the gripping jaws 5. 85

It will be observed that the screw 14 or the pivotal connection of the support 16 serves 95 functionally as a pivotal connection for the handles 1 and 2 when the support 16 is held stationary.

The tool resembles an ordinary pair of pliers with the exception of the gripping jaws 100 and the support 16.

It is thought that the utility and operation of my tool will be fully understood, also that the elements of the invention can be varied or changed without departing from the spirit 105 of the invention.

Having now described my invention what I claim as new, is:—

A tool of the type described, comprising a pair of handle members provided adjacent 110

their forward ends with enlarged portions, a rivet for pivotally connecting said enlarged portions together, a gripping jaw carried by each enlarged portion of the handle members, the said gripping jaws being provided with longitudinally grooved confronting faces and having transversely disposed recesses in said confronting faces, said gripping jaws disposed at an angle with respect to said enlarged portions, an inwardly extending support having its forward portion overlying and in parallel relation with the grooved jaws, means extending through

said rivet and engaging said support for adjustably connecting the latter to the enlarged portion of one of said handle members and a screw adjustably mounted in said support and having a socketed lower end which aligns with the transverse recesses in said jaws when the latter are closed. 15

In testimony whereof I affix my signature in the presence of two witnesses.

RUBIN CAPLAN.
